[57] CLAIM

The ornamental design for a ticket automaton, as shown and described.

DESCRIPTION

FIG. 1 is a front elevational view of a ticket automaton, showing my new design;

FIG. 2 is a rear elevational view thereof;

FIG. 3 is a right side elevational view thereof, the left side being identical; and,

FIG. 4 is a top plan view thereof.

The phantom line portions form no part of our claimed design.
